TRAY TABLE

Beatrice Bliss, P.O. Box 47607, Los Angeles, Calif.

Filed Apr. 22, 1960, Ser. No. 60,281

Term of patent 14 years

(Cl. D33—14)

FIG. 1 is a top plan view of a tray table showing my new design;

FIG. 2 is a side elevational view thereof;

FIG. 3 is an end elevational view thereof; and

FIG. 4 is a fragmentary side elevational view, showing the table-supporting legs in folded position at the under surface of the tray.

The dominant features of the design reside in the contour of the top of the bed-tray in association with the unitary substantially H-shaped supporting legs all as substantially shown.

I claim:

The ornamental design for a tray table, substantially as shown and described.
